UNITED STATES PATENT OFFICE

2,437,765

ADJUSTABLE FASTENING DEVICE

Noel Statham, Greenwich, Conn.

Application March 17, 1945, Serial No. 583,203

1 Claim. (Cl. 24—206)

1

My present invention relates to devices for adjustably fastening two articles together, or two pieces of the same article. Devices of similar function are described and claimed in certain prior patents of mine, as for example Re. 19,356 of October 30, 1934. In this type of fastener a slider attached to one part to be fastened is movable along a flexible track which is attached to the second part to be fastened, and such slider is secured at any desired point on the track by means of a releasable clamping or locking member. In the devices of my prior patents, the track members are provided with stop elements of metal which cooperate with the clamping device on the slider. I have found that for many purposes these stop devices may be eliminated and a simple ribbon or track provided of a plastic nature which may be gripped by the clamping device of the slider and a satisfactory union had between the parts to be attached. One advantage of such an arrangement is that the plastic ribbon forming the track may be attached directly, as by sewing, to the part, as for example a garment or other article; whereas my prior devices require that the track comprised of the stop elements be attached to a tape, which in turn is sewn or otherwise affixed to the part to be attached.

It is therefore a principal object of my invention to provide a simple plastic track securable to the work by stitching and desirably provided with cross corrugations to facilitate the action of the clamping member of the slider. It is also a further object to form the track by means of preferably impregnated fabric, e. g., a woven or braided strip or cord.

Further advantages of my invention and other objects thereof to be attained will be apparent from the following detailed description taken with the annexed drawing in which:

Fig. 1 is an enlarged plan view of my improved track with slider attached;

Fig. 2 is a longitudinal sectional view thereof taken along line 2—2 of Fig. 1;

Fig. 3 is a view taken along line 3—3 of Fig. 1 on a still larger scale than Fig. 1;

Fig. 4 is a cross sectional view of a modification in which the track is formed of impregnated braided or woven fabric;

Fig. 5 is a perspective view of a track consisting of a plastic-impregnated cord;

Fig. 6 is a cross section on line 6—6 of Fig. 5.

As shown in Fig. 1, my improved track consists of a ribbon 10 of an appropriate plastic or semi-plastic material, as for example Celluloid or any

of the many Celluloid-like plastics, which will permit stitching of the material while having enough body or stiffness to withstand the gripping action of the slider. Among such other plastics as may be used are cellulose acetate, polyvinyl alcohol, polyvinyl acetals, ethyl cellulose, various of the nylons, methyl methacrylates, and many others. In Fig. 1 the plastic ribbon or track 10 is shown secured to a fabric 11 by a central longitudinal line of stitching 12. Adapted to engage the track or ribbon 10 is a slider denoted generally by 15. Slider 15 comprises a body portion 16 of generally C shape cross section which by virtue of this shape is adapted to be secured to track 10 by engaging beneath the same, as best shown in Fig. 3. To facilitate this, the track 10 may be made of T shape cross section (Fig. 3). Said body portion 16 also has upstanding ears 17—17 which support the clamp or locking element denoted generally by 18 (Fig. 2). Said element 18 comprises a tab portion 18a and a cam portion 18b, and is further provided with trunnions 19—19, Fig. 3, to engage apertures in the ears 17—17. The material forming said ears is taken from the body portion 16, thereby forming an aperture in said body portion denoted 20, Fig. 2, to enable the cam or locking portion 18b to come into contact with the track 10. The body portion 16 also terminates in a loop 21 to which is adapted to be attached the fabric 22 or other article to be joined, the tab 23 of such fabric passing through the loop and being secured to the body of the fabric 22 by stitching 24.

As mentioned above, the outer surface of the track 10 preferably is provided with indentations or corrugations having grooves 25 and ribs 25a, as shown best in Figs. 1 and 2, whereby to enable the locking element 18b to engage a groove 25 of the corrugations.

A further feature of my invention consists in making the cam or locking element 18b with a groove or cutout portion 26 disposed centrally thereof whereby to avoid cutting the stitching 12. (See particularly Fig. 3.) A stop for the slider at the non-entrant end of the track 10 may be provided in the form of a button or other element 27, Fig. 1.

In Figs. 5 and 6 I show a track 10' formed of a braided cord preferably stiffened by being impregnated with a suitable plastic and secured to the work 11' by a line of stitching 12'. The track 10' so formed may be engaged by a slider the same as in the case of track 10. If desired the ends of the cord may be brought through and

under the work as shown in Fig. 5. It will be evident that the comparatively rough surface of the braided cord will facilitate the gripping action of the slider.

In Fig. 4 an impregnated braid or woven tape 10a has interposed between it and the work, a spacer element or tape 28 to provide room for the portion 16 of the slider 15.

It will be obvious from the foregoing that my device is useful in a wide variety of applications, especially in the garment field and in pocket-books, brief cases and the like.

I claim:

A fastening and adjustment device for securingment to two parts and for adjustably securing the two parts together, said device having a track consisting of an integral strip of flexible tape-like material for securement directly to one of said parts, and a slider for securement to the other of said parts, said slider engaging beneath the edges of said track and having its free edges

spaced from one another to permit the direct securement of the track along its longitudinal central portion, said slider being movable along the track and having a clamp coacting with the strip for fixedly securing the slide at a desired point on said track by a clamping action directly upon the flexible tape-like material.
